UNITED STATES PATENT OFFICE.

WILLIAM H. STEDMAN, OF HARTFORD, CONNECTICUT, ASSIGNOR TO THE MERROW MACHINE COMPANY, OF HARTFORD, CONNECTICUT, A CORPORATION OF CONNECTICUT.

FEEDING MECHANISM FOR SEWING-MACHINES.

SPECIFICATION forming part of Letters Patent No. 733,922, dated July 14, 1903.

Application filed October 21, 1902. Serial No. 128,160. (No model.)

To all whom it may concern:

Be it known that I, WILLIAM H. STEDMAN, a citizen of the United States, residing in the city and county of Hartford, State of Connecticut, have invented a certain new and useful Feeding Mechanism for Sewing-Machines; and I do hereby declare the following to be a full, clear, and exact description of the same, reference being had to the accompanying drawings, forming a part of this specification, and to the figures of reference marked thereon.

This invention relates to the feeding mechanism of sewing-machines, including devices for controlling the action of the feed near the edge of the material, the object of the invention being to improve the general construction and operation of these portions of the machine.

The invention consists in the provision of a positively-driven "four-motion" feed and an edge controller and in certain peculiarly constructed and assembled driving mechanism for the said feed and edge controller, all as hereinafter fully described.

The improvements constituting the present invention are shown in connection with a well-known type of machines commonly designated "Merrow high-speed overseaming-machines;" but the said improvements are also applicable to and adapted for use with other types of sewing-machines.

In the accompanying drawings, Figure 1 is a front elevation of a machine with the present improvements applied thereto, but with portions of the machine mechanism removed. Fig. 2 is an end elevation of the said machine and improvements as viewed from the left hand of Fig. 1, a portion of the machine-frame being broken away. Fig. 3 is a detail partly in cross-section, taken on the line 3-3 of Fig. 2, and illustrates also the manner of assembling and disassembling the parts. Fig. 4 is an elevation of the feed-carrier and adjacent elements detached from the machine and with a portion broken away. Fig. 5 is a view similar to Fig. 4, illustrating the edge-controlling mechanism. Fig. 6 is a view, partly in plan and partly in section, showing the relative positions of the feed and edge

controller carriers and also the means whereby the said carriers are actuated. Fig. 7 is an elevation and edge view of a key or tool for use in assembling and removing the feed-eccentric.

Like reference-numerals throughout the several figures of the drawings denote the same parts.

The number 10 indicates the main frame of the machine; 11, a head formed on a frame 11^a, secured to the said main frame.

12 indicates the main or driving shaft; 13, the driving-pulley; 14, an auxiliary shaft above and parallel with the main shaft; 12^a 14^a, cam-cylinders located, respectively, on the shafts 12 and 14 and having intermeshing gears 12^b 14^b, whereby the shafts and cam-cylinders are caused to rotate in unison, and 14^c denotes an eccentric-pin located in the end of the shaft 14. The pin 14^c (through mechanism not shown) actuates the needle of the machine, and the cam-cylinders 12^a 14^a (also through mechanism not shown) actuate the stitch-forming implements or loopers that coöperate with the said needle; but as the stitch-forming mechanism is well known and forms no part of this invention an illustration and detailed description thereof are deemed unnecessary.

The number 15 indicates the needle-plate, supported beneath the head 11 on the head-frame 11^a or in any other suitable manner, and 16 indicates the presser-foot, supported by the said head and, as usual, provided with proper lifting mechanism.

The feed-carrier 17 and the edge-controller carrier 18, forming part of the present invention, are located side by side in the machine and at their forward ends, respectively, have adjustably secured thereto by screws 17^a 18^a the feed-dog 17^a and the edge-controller 18^a. At their rear ends the carriers 17 18 are pivotally supported on a pin 19, mounted in the head-frame 11^a or on other suitable fixed portion of the machine. The carriers 17 18 are adapted to rock on the pin 19 in making the usual vertical reciprocations, and the carrier 17 is also moved longitudinally with reference to the said pin to effect the usual horizontal reciprocations of the feed. The feed-

carrier 17 preferably does not engage the pin 19 directly; but the latter is provided with a pivotal block 19^a, entering an elongated opening 17^b at the rear end of the carrier and forming a support on which the carrier is adapted to slide in a manner well understood.

The feed-dog 17^a extends through suitable openings in the needle-plate 15 to engage and feed the material confined between the needle-plate and the presser-foot, and the edge-controller 18^a extends above the needle-plate and engages the material while being fed near the edge thereof and adjacent the feed-dog to force the said material against the under side of the presser-foot, thereby retarding and controlling the feeding action of the dog and preventing the stretching or pouting of the material at its edge. To properly perform their respective functions, the feed-dog 15 and edge-controller and their carriers 17 18 are raised and lowered simultaneously by an eccentric 12^c, formed on or secured to the shaft 12, which eccentric also forms the support for the forward ends of the carriers. The eccentric 12^c is adapted to rotate within a block 20, common to both carriers and working in bearings 17^c 18^c in the said carriers. Upon the rotation of the eccentric the block 20 is actuated to raise and lower the said carriers, the opening in the said carriers being of suitable length to permit the block 20 to slide therein and to permit of the longitudinal movement of the feed-carrier.

For convenience in constructing and assembling the parts the elongated opening or bearing 17^c of the feed-carrier 17 is provided with a separable cap 17^d and, further, with an opening or slot 17^e, through which the screw 18^f, securing the edge-controller to its carrier 18, may be readily reached and manipulated.

The horizontal movements of the feed are effected by an eccentric 21, secured to the shaft 12 in a manner to be hereinafter explained. The eccentric 21 is encircled by a strap 22, having a rearwardly-extending portion pivotally connected with the carrier 17 by the bolt 17^d, as shown in Figs. 2 and 6. Upon the rotation of the eccentric 21 the carrier 17, through the strap 22, is reciprocated horizontally, the said carrier sliding freely on the blocks 20 19^a.

It will now be obvious that upon the rotation of the shaft 12 the eccentric 12^c imparts positive and simultaneous vertical reciprocation to the carriers 17 18, and therefore to the feed-dog and edge-controller, also that the eccentric 21 imparts positive horizontal motions to the said feed-carrier and its dog.

In connection with the shaft 12, the eccentric 21, and the strap 22 means are provided whereby the assembling and dissembling of these elements may be rapidly and easily accomplished. To carry into effect this feature 65 of the invention, the end of the shaft 12 is preferably provided with a threaded extension 12^d, upon which the eccentric 21 is

mounted, the latter being drilled and tapped to receive the threaded portion of the shaft. The eccentric 21 is of somewhat greater thickness than the eccentric-strap 22 and when in position projects beyond the said strap, as seen in Figs. 1, 3, and 6. A groove or channel 21^a is formed in its outer face, while the eccentric-strap 22 at its end encircling 75 the eccentric is provided with diametrically-opposed retaining-shoulders, which in this instance are formed by notches, as shown at 22^a.

The numeral 23 indicates what may be termed a "key," constructed, preferably, of thin sheet metal having one edge cut out to form the recess 23^a and projections 23^b. Should it be desired to remove the eccentric 12^c for the purpose of substituting one of different throw to vary the length of feed or for other reasons, the said eccentric is rotated to bring its channel 21^a into alinement with the notches 22^a, as shown in Fig. 2. The key 23 is then placed in position with its edge 23^a in the channel 21^a and the projections 23^b in the notches 22^a. The eccentric 21 is thereby held against rotation in the strap 22 and upon the proper rotation of the shaft 12 is caused to travel outward on the threaded portion of 95 the latter until it becomes separated therefrom. On the other hand, should it be desired to place the eccentric in position on the shaft it is inserted in the eccentric-strap, the key is placed in position to engage the channel and the notches, as before explained, and pressed against the eccentric to hold the latter in contact with the shaft end, while the shaft is rotated to cause the threaded portion to enter the eccentric and travel inward 105 therein until the latter is in position.

It will be clear that the length of the horizontal movements of the feed or the "length" of the feed, as it is commonly called, is determined by the throw or eccentricity of the eccentric 21. Eccentrics 21 of different throws, respectively, are to be provided for use with the machine, each of which eccentric is drilled and tapped parallel with its axial center to fit the threaded end 12^d of the shaft 12, the several eccentrics being properly threaded to screw up to substantially a common relative position upon the shaft, so that the feed shall be properly timed. The differentiation in the throw of the eccentrics is determined by the 110 distance between the center of the drilled and tapped hole and the respective centers of the eccentrics; further, the said eccentrics are all of a uniform and suitable diameter to fit and run in the strap 22. -

The described method of securing the eccentrics 21 to the shaft 12 is of great utility in that the eccentrics may be placed in and removed from their operative position by the application of a suitable instrument to the 130 outer or exposed face of the eccentric, and in removing an eccentric from its operative position the application of force to its opposite or inner face to start it from its seat is un-

necessary, which feature is particularly useful, as the opposite or inner face is inaccessible in the machine shown.

By the construction illustrated and described the feed -eccentric can readily be placed in operative position, is firmly and substantially held while in use, and at the same time is easily removable.

Having thus described my invention, what I claim as new, and desire to secure by Letters Patent, is—

1. A sewing-machine feeding mechanism embodying an oscillating and horizontally-movable feed-dog carrier, an edge-controller, an oscillating carrier therefor, a fixed pivotal support common to the rear ends of both carriers and with reference to which the feed-dog carrier is longitudinally movable and the edge-controller has oscillatory movement only means for oscillating both carriers and means for moving the feed-dog carrier longitudinally, substantially as described.

2. A sewing-machine feeding mechanism embodying an oscillating and horizontally-movable feed-dog carrier, a block upon which the end of the said carrier is slidably mounted, an edge-controller, an oscillating carrier therefor, a fixed pivotal support common to the said block and the rear end of the edge-controller carrier means for oscillating both carriers and means for moving the feed-dog carrier longitudinally; substantially as described.

3. A sewing-machine feeding mechanism embodying a feed-dog carrier and means for moving the same vertically, an eccentric for driving said feed-dog carrier longitudinally, a main shaft, said eccentric and shaft being joined to each other by a threaded portion of one screwing to a threaded portion of the other, whereby eccentrics may be substituted to vary the feed; substantially as described.

4. A sewing-machine feeding mechanism embodying a vertically-oscillating and horizontally-movable carrier, a drive-shaft having a threaded portion, an eccentric mounted on the said threaded portion and connected

with the carrier to impart horizontal reciprocation to the feed; substantially as described.

5. A sewing-machine feeding mechanism embodying a vertically-oscillating and horizontally-movable carrier, a drive-shaft having a threaded portion, an eccentric mounted on the said threaded portion and connections between the same and carrier to impart horizontal reciprocation to the feed, and means for locking the said eccentric against rotation with its shaft for facilitating the application and removal of said eccentric, substantially as described.

6. A sewing-machine feeding mechanism embodying a vertically-oscillating and horizontally-movable feed-dog carrier, a shaft having a threaded portion, an eccentric having a channeled face and adapted to be mounted on the threaded shaft portion, an eccentric-strap connecting the eccentric and the carrier and having diametrically-opposed notches adapted to aline with the channel in the eccentric, in combination with a securing implement adapted to engage the said channel and notches for locking the eccentric against rotation in the strap, substantially as described.

7. A sewing-machine feeding mechanism embodying a vertically-oscillating and horizontally-movable feed-dog carrier, a drive-shaft therefor having a threaded portion, an eccentric having a face channeled for the reception of a securing implement and adapted to be mounted on the threaded portion of the shaft, an eccentric-strap connecting the eccentric and carrier and having diametrically-opposed notches adapted to aline with the channel in the eccentric, a key forming a securing implement and having a recessed portion to engage the channel and projecting portions to engage the notches for locking the eccentric against rotation in the strap, substantially as described.
